JAMES W. KELCH, JAMES J. SUNDAY, AND FREDRICK SCHLUETER, OF DETROIT,
MICHIGAN.

HEATER FOR AUTOMOBILES.

Application filed February 12, 1925. Serial No. 8,779.

To all whom it may concern:

Be it known that we, JAMES W. KELCH, JAMES J. SUNDAY, and FREDRICK SCHLUETER, citizens of the United States of America, residing at Detroit, in the county of Wayne and State of Michigan, have invented certain new and useful Improvements in Heaters for Automobiles, of which the following is a specification, reference being had therein to the accompanying drawing.

This invention relates generally to heating apparatus for motor vehicles and refers more particularly to heaters in which air from the atmosphere is heated within a suitable shell by the exhaust gases from the engine of the motor vehicle.

One of the essential objects of the invention is to provide a compact and efficient heater of this type in which the exhaust gases from the engine are directed by positive means into the tubes of the core to facilitate the passage of the gases through the shell and thereby eliminate back pressure on the motor.

Another object is to provide a heater that may be easily attached to or detached from spaced portions of the exhaust conduit of the vehicle and that may be quickly assembled or taken apart so that it may be readily cleaned or repaired.

A further object is to provide the heater with a core in which the tubes for the exhaust gases are preferably brazed at their opposite ends to the headers to prevent the parts working loose causing leakage of exhaust gases.

With the above and other objects in view the invention consists in certain novel features of construction, combinations and arrangements of parts as will be more fully described and particularly pointed out in the appended claims.

In the accompanying drawing;

Figure 1 is a fragmentary side elevation of a vehicle with a heater embodying our invention attached thereto.

Figure 2 is an enlarged vertical longitudinal sectional view through the heater.

Figure 3 is a sectional view taken on the line 3—3 of Figure 2.

Figure 4 is a sectional view taken on the line 4—4 of Figure 2.

Figure 5 is a sectional view taken on the line 5—5 of Figure 2.

Referring now to the drawing in which like characters of reference designate corresponding parts throughout the several views, the numeral 1 designates a motor vehicle having an engine exhaust conduit 2 to which the heater 3 embodying our invention is preferably attached. As shown, the heater 3 is preferably provided with an outer shell or casing 4 that is preferably cylindrical in form and is closed at its opposite ends by substantially funnel-shaped heads 5 and 6 respectively sleeved upon portions 2' and 2'' of the exhaust conduit 2. Thus, the tubular portion 5'' of the head 5 constitutes an inlet port for the exhaust gases, while the tubular portion 6'' of the head 6 constitutes an outlet passage. Any suitable means may be employed for conveying air from the atmosphere to the shell 4 and from the shell to the body 5' of the vehicle. As shown, a suitable pipe 6' extends forwardly from the shell 4 adjacent to the forward end thereof, and terminates in a flared portion 7, preferably adjacent to the fan 8 of the engine, while a second pipe 9 extends rearwardly from the shell 4 adjacent to the rear end thereof and connects into a suitable air register 10 which may be located at any convenient place such as in the floor of the vehicle body.

In order that the exhaust gases from the engine will not mix with the air discharged by the conduit 6 into the shell 4, we preferably provide the shell with a suitable core 11. As shown, this core preferably comprises two headers 12 and 13 respectively and a plurality of spaced straight tubes 14 that extend between said headers 12 and 13. These tubes may be made of any suitable material such as copper or aluminum and are preferably arranged closer together at their rear ends so that the desired concentration of heat may be obtained. To prevent back pressure on the engine as well as objectionable noise, the forward header 12 is preferably provided at the centre thereof

with an inwardly extending concave portion 15, and the tubes 14 are preferably provided at their forward ends with flared portions 16 that are secured in the concave portion 15 of the header. To provide a strong and durable construction, the tubes 14 are preferably brazed to the headers 12 and 13 respectively. Thus, the tubes are not likely to work loose while the heater 10 is in use.

In order that the shell 4 and core 11 of the heater may be easily and quickly assembled or taken apart, the header 12 is preferably clamped between the flanges 17 and 18 respectively of the shell 4 and head 5 by means of suitable bolts 19, while the header 13 is preferably bolted to an annular plate 20 that is clamped between the flanges 21 and 22 respectively of the shell 4 and head 6 by means of the bolts 23. To facilitate attachment of the heater to the exhaust pipe 2, the tubular portions 5 and 6 respectively of the heads 5 and 6 are sleeved upon the adjacent portions of the conduit 2 and are preferably clamped in position thereon by means of the split collars 26. Thus, with this construction, the heater may be readily removed from the conduit 2 and taken apart to be cleaned or repaired.

If desired, a suitable baffle 27 may be sleeved upon certain of the tubes 14 of the core approximately midway of the shell for deflecting downwardly the air discharged from the conduit 6. Thus a better circulation of the air is obtained within the shell 4. A cover 28, preferably of asbestos may also be provided for the shell to insulate the same from the cold.

In use, air from the atmosphere will be discharged from the conduit 6 into the shell 4 where it will be heated by the exhaust gases passing through the tubes 14 of the core and will be subsequently discharged into the conduit 9 leading to the register 10. The exhaust gases from the engine will be discharged by the forward portion 2' of the exhaust conduit against the concave portion 15 of the header 12 which will direct the gases to the flared inlet ends 16 of the tubes, consequently, the gases will enter the outermost tubes 14 as readily as they will enter the innermost or centrally disposed tubes. As a result, all of the tubes are heated substantially equally. Moreover, the arrangement is such that the exhaust gases pass in substantially a straight line from the forward portion 2' of the exhaust conduit to the rear portion 2'', consequently a free and unobstructed passage is provided for the gases through the heater.

While it is believed that from the foregoing description the nature and advantages of our invention is readily apparent, we desire to have it understood that we do not limit ourselves to what is herein shown and

described and that such changes may be resorted to when desired as fall within the scope of what is claimed.

What we claim as our invention is:

1. A heater for motor vehicles including a shell having inlet and outlet ports for the exhaust gases of the motor, a plurality of tubes extending between said inlet and outlet ports, and means opposite to and in rear of the inlet port for directing the exhaust gases into the tubes, said means being so constructed as to eliminate back pressure on the motor. 75

2. A heater for motor vehicles including a shell having inlet and outlet ports in the opposite ends thereof for the exhaust gases of the motor, a plurality of tubes extending longitudinally of the shell between said inlet and outlet ports, and means in rear of the inlet port for directing the exhaust gases into the tubes, said means being so constructed as to eliminate back pressure on the motor. 80

3. A heater for motor vehicles including a tubular shell having substantially aligned inlet and outlet ports for the exhaust gases of the motor, a core having a plurality of tubes extending longitudinally of the shell between the said inlet and outlet ports, and a header for the tubes opposite to the inlet port constituting means for directing the exhaust gases from the inlet port into the tubes, said header being constructed and arranged with respect to said inlet port to eliminate back pressure on the motor. 90

4. A heater for motor vehicles including a shell having inlet and outlet ports for the exhaust gases of the motor, a core having tubes extending between said inlet and outlet ports, and a header having a concave portion opposite to the inlet port aforesaid for directing the exhaust gases into the tubes, said header and concave portion being arranged with respect to said inlet port to eliminate back pressure on the motor. 100

5. In a heater for motor vehicles, the combination with a tubular shell having substantially aligned inlet and outlet ports for the exhaust gases of the motor, and a plurality of tubes extending longitudinally of the shell for conveying the exhaust gases in substantially a straight line from the inlet port to the outlet port, of means opposite to the inlet port for directing the exhaust gases into the tubes whereby the passage of gases through the tubes will be substantially uniform, said means being so constructed as to eliminate back pressure on the motor. 115

6. In a heater for motor vehicles, the combination with a tubular shell having inlet and outlet ports for the exhaust gases of the motor at the opposite ends thereof, and an inwardly flared portion immediately in rear of the inlet port, a core having tubes 125

extending longitudinally of the shell between said inlet and outlet ports, and a header for the tubes having a concave portion opposite to the flared portion aforesaid 5 for directing the exhaust gases into the tubes so that the said gases will flow freely in substantially a straight line from the

inlet port through the tubes to the outlet port.

In testimony whereof we affix our signatures.

JAMES W. KELCH.

JAMES J. SUNDAY.

FREDRICK SCHLUETER.
